UNITED STATES PATENT OFFICE

1,982,432

CEMETERY MONUMENT

Rubert A. Hull, Andover, Ill.

Application June 10, 1933, Serial No. 675,180

15 Claims. (Cl. 47—38)

My invention relates to cemetery monuments and particularly to those having an inclosed recess or alcove for holding flowers or growing plants.

- 5 The principal object of my invention is to provide improved means for ventilating the inclosed recess, through which air may circulate to keep the flowers or plants in a fresh and growing condition.
- 10 Another object is to provide means for collecting rainfall and conducting the water to a reservoir provided below the recess, from which the water is drawn by the plants or flowers by capillary attraction.
- 15 Other objects and advantages of my invention will be apparent to those skilled in the art after a consideration of the following detailed description, taken in conjunction with the accompanying drawing wherein:
- 20 Figure 1 is a front elevational view of a monument embodying my invention.

Figure 2 is an enlarged sectional view taken on the plane of line 2—2 of Figure 1, and

Figure 3 is a sectional view taken on the plane 25 of line 3—3 of Figure 2.

The monument comprises an outer case 5 and an inner case 6 both of which are constructed of a rust resisting metal. The outer case 5 is substantially rectangular and includes a front sheet 30 7 and a back sheet 8 which are connected to side sheets 9 and to a top 10 and bottom 11. The top 10 is preferably arcuate, as shown in Figure 1. The case 5 is mounted on a suitable base 12, preferably of stone or similar material, and is secured thereto by bolts 13 which extend through bottom 11 and are anchored in base 12. An opening is formed in front sheet 7 and a door 14 is provided to close the opening. The door 14, when closed, is flush with front sheet 7 and is hingedly mounted on one side of the opening. A lock 15 serves to secure the door in closed position. The panel 16 of door 14 is formed of glass or other transparent material to permit of view into inner 40 case 6.

The inner case 6 is supported within the case 5 and is so positioned that an opening which is formed in the front thereof, is disposed adjacent the opening in outer case 5. An outwardly extending flange 21 is formed along the top and sides of the opening in case 6. This flange 21 engages against a jamb 22 which is secured to the inner face of sheet 7 adjacent the edge of the opening therein. The jamb 22 is offset slightly 55 inwardly away from door 14. The lower ends of

side flanges 21 rest upon a sill 24 which is provided adjacent the lower edge of the opening in sheet 7.

The inner case 6 is removable so as to permit access into case 5 to secure bolts 13. Small articles may be stored in the bottom of case 5 60 and which are also accessible by removing inner case 6.

The inner case 6 is of substantially rectangular shape and is slightly smaller than outer case 5 so that when it is in position within outer case 5 the sides of inner case 6 are spaced from the sides of the outer case. The top member of case 6 is arcuate and is concentric with the lower edge of the opening in the front thereof to permit the case to be swung into or out of position. The 70 construction of case 6 is such as to form a compartment adapted to be mounted within the outer case 5 for displaying flowers, plants, etc., as will be described later. This construction is distinguished from that of an ordinary jardinière with 75 its flowerpot.

A groove or gutter 25 is formed on the outer face of jamb 22, and is disposed between the outer edge of flange 21 and an inwardly extending drip flange 26 formed around the edge of 80 door 14. Water which leaks in around door 14 drips off the edge of drip flange 26 into gutter 25 and is thereby conducted downward to a weeping hole 27 located below sill 24 from which it flows outwardly below the lower edge of door 14. 85

A division member or table 31 is removably mounted in inner case 6 and is spaced upwardly from the bottom thereof to form an upper recess 32 and a lower recess 33. The front edge of table 31 rests upon sill 24 and the rear edge 90 is supported by a pair of pins 34, which are secured to the rear edge of table 31 and project into holes provided in the back of case 6. The table 31 is secured against removal when door 14 is locked in closed position. This is facilitated by means of a plurality of pins 30 which are secured along the lower edge of door 14 and project inwardly therefrom and extend over the front edge of table 31. By reason of pins 30 being attached to door 14 in this manner, table 100 31 is secured against removal whenever door 14 is closed, whether or not panel 16 is used. The upper recess 32 is adapted to receive flowers or plants which are supported on table 31 and are visible through panel 16 of door 14. A photograph or any similar article may also be positioned in recess 32. The recess 33 comprises a reservoir for storing water for the flowers or plants in recess 32.

The flowers or growing plants are disposed in 110

holders 36 provided for that purpose. The holders 36, two of which are shown in Figure 3, comprise an upper flaring portion 37 and a lower cylindrical portion 38. The portion 38 of each holder extends through an opening in table 31 and projects into reservoir 33. Soil is provided in holder 36. A plurality of openings 39 are formed in the bottom of holder 36 to permit water to enter the holder and to be carried by capillary attraction through the soil to the plant roots. The holders 36 are secured to table 31 by means of pins 40 which extend through the holders below table 31.

Water is provided in reservoir 33 from rainfall which is collected in pockets 41 provided on the outer face of side sheets 9. A conductor tube 42 extends inwardly from each pocket 41 and projects into reservoir 33. During drought periods water may be added by raising table 31. The conductor tubes 42 are preferably formed of metal and inside of inner case 6 after case 6 has been positioned in case 5 and before table 31 is mounted in place. If, however, it is desired to form tubes 42 of a resilient material such as rubber, the tubes may be permanently secured to pockets 41. As inner case 6 is placed in position the ends of tubes 42 will spring into the openings provided therefor in the sides of case 6, thereby making it unnecessary to remove the tubes each time case 6 is removed.

An over-flow member comprising a pipe 45 having a cross T 46 secured to the upper end thereof is removably mounted in a drain hole in the bottom of reservoir 33. A short pipe or nipple 45a extends downwardly from the drain hole and projects into the upper end of a vertical conductor pipe 47. The lower end of pipe 47 projects into a horizontal conductor pipe 48 which is embedded in base 12 and extends rearwardly thru the outer face thereof. The water is permitted to rise in reservoir 33 until it reaches the height of cross T 46 whereupon any additional water drains through T 46, pipe 45, and nipple 45a and is carried out by conductors 47 and 48. Conductor 47 is vertically disposed and extends downwardly from the drain hole in reservoir 33 and into conductor 48 which is disposed horizontally in base 12. A drain tube 49 is provided in the bottom of outer case 5 and extends into conductor 47. A screen 50 is provided on the outer end of conductor 48 to prevent insects from entering therein. The water in reservoir 33 may be drained by removing the over-flow member whereupon the water escapes through the drain hole and is carried away by conductors 47 and 48.

Ordinarily there is no water in conductors 47, 48 and over-flow members 45, 46. At such times a current of air is permitted to pass through these members and upwardly through holes 52 in table 31. The air passes through recess 32 and out through holes 53 in the top of case 6 and holes 54 in front sheet 7. The holes 54 are preferably located behind the raised letters 55 which form the inscription on the face of the monument. The letters 55 are hollow and are open at their lower ends to permit air to pass therethrough.

By this construction air is permitted to pass through recess 32 to keep the flowers or plants therein in a fresh and growing condition. Since the air also passes through water reservoir 33 the water remains fresh and pure.

Space is provided in the upper portion of case 5 above inner case 6 to accommodate a memento

box 57, which is secured by cap screws 58 or similar devices to back sheet 8. The memento box 57 may be of any desired shape or size consistent with the size of the space between casings 5 and 6.

Having thus described my invention, what I claim as new and desire to secure by Letters Patent is:—

1. A monument comprising an inclosed outer case, an inner case, a division member removably mounted in said inner case, a recess in the upper portion of said inner case, a water reservoir in the lower portion of said inner case, a holder for flowers or growing plants removably positioned in said recess, said holder having a cylindrical portion formed on the lower end thereof and extending into said reservoir, and means for admitting a current of air into said recess, whereby the flowers or plants in said holder are maintained in growing condition.

2. A monument comprising an inclosed outer case, an inner case, a division member within said inner case, a recess above said division member, a water reservoir below said division member, a holder for flowers or growing plants positioned in said recess, said holder supported on said division member, a cylindrical portion formed on the lower end of said holder and adapted to extend through a hole in said division member and project into said reservoir, and means for admitting a current of air into said recess, whereby the flowers or plants in said holder are maintained in growing condition.

3. A monument comprising an inclosed outer case, an inner case, means for supporting flowers or growing plants removably mounted in said inner case, and means for admitting a current of air into said inner case, whereby the flowers or plants disposed therein are maintained in growing condition.

4. A monument comprising an outer case, an inner case removably mounted in said outer case, said inner case having a recess visible thru a side of said outer case, a water reservoir in said inner case below said recess, and a holder for flowers or growing plants removably mounted in said recess and adapted to extend into said reservoir.

5. A monument comprising an inclosed outer case, an inner case, a recess in the upper portion of said inner case, a water reservoir in the lower portion of said inner case, a holder for flowers or growing plants positioned in said recess, said holder having a member extending into said reservoir, means for collecting rainfall and conducting it to said reservoir, an over-flow in said reservoir, and an outlet connected with said over-flow, said outlet also serving to admit a current of air into said recess, whereby the flowers or plants in said holder are maintained in growing condition.

6. A monument comprising an outer case, an opening in one side of said outer case, a closure for said opening, means for securing said closure in closed position, an inner case supported in said outer case, a removable member in said inner case, and means on said closure to prevent removal of said removable member when said closure is secured in closed position.

7. A monument comprising an inclosed outer case, an inner case, a recess in the upper portion of said inner case, a water reservoir in the lower portion of said inner case, a holder for flowers or growing plants positioned in said recess, said holder having a member extending into said

- reservoir, and an over-flow member removably mounted in a drain hole in said reservoir, said over-flow member when in place serving to determine the maximum amount of water in said reservoir and when removed to permit the water to drain out of said reservoir, conductor means for conducting the water away from said drain, said conductor means and said over-flow member also serving to admit a current of air into said inner case. 5 to drain said outer case, said conductor and over-flow member also serving to permit passage of a current of air into said inner case, which air current also passes through said openings in the top of said inner case and said outer case. 80
8. A monument comprising an inclosed case, a recess for receiving flowers or growing plants disposed within said case, an inscription on an outer face of said case, said inscription formed of a plurality of raised hollow letters, openings in the lower ends of said letters, and openings in said case behind said letters, whereby air is admitted to said recess to keep the flowers or plants therein in fresh and growing condition. 15
9. A monument comprising a base, an inclosed outer case mounted on said base, a door in one side of said outer case, a transparent panel in said door, ventilating openings adjacent the top of said outer case, an inner case supported in said outer case, ventilating openings in the top of said inner case, a division member in said inner case, ventilating openings in said division member, means to prevent removal of said division member when said door is closed, a recess above said division member adjacent said door, a water reservoir below said division member, a holder for flowers or growing plants supported on said division member, a cylindrical portion secured to the lower end of said holder and adapted to extend through a hole in said division member and project into said reservoir, a removable over-flow member engaging an opening in the bottom of said reservoir, said over-flow member when in place serving to determine the maximum amount 20 of water in said reservoir and when removed to permit the water to drain out of said reservoir, a conductor for conducting the water out of the monument and a connection with said conductor 25 to drain said outer case, said conductor and over-flow member also serving to permit passage of a current of air into said inner case, which air current also passes through said openings in the top of said inner case and said outer case. 30
10. A monument comprising an enclosed outer case, an inner case removably supported in said outer case, said inner case having a recess and a water reservoir, means for separating said recess and said reservoir, and a holder for flowers or growing plants removably mounted in said recess. 35
11. A monument comprising an enclosed outer case, an inner case removably supported in said outer case, said inner case having a recess and a water reservoir, means for separating said recess and said reservoir, and a holder for flowers or growing plants removably mounted in said recess. 40
12. A monument comprising an enclosed outer case, an inner case removably supported in said outer case, said inner case having a recess and a water reservoir, means for separating said recess and said reservoir, a holder for flowers or growing plants removably mounted in said recess, and water receiving means on said holder extending into said reservoir. 45
13. A monument comprising an outer case, an opening in one side of said outer case, and an inner case removably mounted in said outer case, said inner case having a recess visible thru said opening in said outer case. 50
14. A monument comprising an outer case, an opening in one side of said outer case, and an inner case supported in said outer case, said inner case having a recess visible thru said opening in said outer case. 55
15. A monument comprising an outer case, an opening in one side of said outer case, an inner case within said outer case, a recess in said inner case, and an opening in one side of said inner case registering with said opening in said outer case, whereby said recess is visible thru said opening in said inner and outer cases. 60
